METHOD AND APPARATUS FOR PUMPING
AND HEATING OIL WELLSTheodore J. Nowak, San Pedro, Calif., assignor
to Union Oil Company of California, Los An-
geles, Calif., a corporation of California

Application October 23, 1950, Serial No. 191,575

10 Claims. (Cl. 166—17)

1

This invention relates to a method and apparatus for heating oil wells whereby the rate of oil flow and the net yield of oil can be increased. More particularly, this invention relates to a method and apparatus for the combustion of a part of the oil production within the well bore in a manner wherein a simultaneous heating and pumping of the oil flow from the formation is effected.

Many methods have been employed in the prior art for heating oil wells in order to increase production, e. g., by electrical means and by injecting into the well heat transfer agents such as steam, hot oils and the like. In other modifications natural gas or other fuel has been combusted within the well bore. Such methods have generally met with little or no commercial success partly due to the type of apparatus employed and poor heat transfer obtained thereby and partly due to the fact that the hot oil is rapidly cooled during transit from the oil-bearing formation to the earth surface with the resultant deposition of wax and other materials. The wax and other deposits cause rapid plugging, fouling of the rods, pumps and other elements.

A new method for heating wells has been discovered which combusts a minor portion of the oil by a submerged flame technique within the well bore in close proximity to the oil-bearing formation. The combustion gases are employed to transfer heat to the surrounding oil and assist in the pumping of the heated oil. The heated gases and oil are preferably also passed through a heat transfer zone, wherein a substantial portion of the heat generated is transmitted through radiation or convection to the surrounding oil-bearing formation.

It is an object of this invention to heat an oil-bearing formation and simultaneously recover oil from the oil-bearing formation wherein a minor portion of the oil production is combusted and the heated products from such combustion are passed through a heat transfer zone wherein a major part of the heat generated thereby is transmitted to the oil-bearing formation.

It is another object of this invention to provide an apparatus for simultaneously pumping an oil-bearing formation and heating such oil-bearing formation, which apparatus employs a portion of the oil flow as fuel therefor.

It is another object of this invention to decrease pumping costs in the production of waxy crude oil or other crudes which deposit gums or solids upon cooling.

It is another object of this invention to utilize

2

a portion of the oil production within a well bore in order to heat the oil-bearing formation and pump or assist in pumping such oil production from the oil pool at the bottom of the well.

It is another object of this invention to combust oil within an oil well bore by a submerged combustion technique wherein a maximum transfer of heat from the combustion zone to the surrounding oil is effected and wherein the heated oil resulting therefrom is employed to heat the oil-bearing formation.

Other objects of this invention will become apparent to those skilled in the art as the description thereof proceeds.

15 Briefly, this invention relates to a new method for heating oil-bearing formations and pumping the oil produced therefrom. The invention is in part based on a new submerged burner. Oxygen or other molecular oxygen-containing gas, with or without preheating, is passed from the burner into a combustion zone which is surrounded by crude oil. A portion of the crude oil surrounding the combustion zone is drawn into contact with the oxygen and is combusted as a result thereof. The heat generated in the combustion zone is radiated or otherwise transmitted to the surrounding crude oil.

20 In a preferred modification of the invention the burner is located below the liquid level within the bore hole such that a continuous supply of crude oil may be drawn into contact with the combustion zone and passed upwardly through a Venturi constriction and thence to the earth's surface. A plurality of heat radiating vanes surrounds the Venturi constriction to facilitate the transfer of heat from the oil and gases carried therein to the surrounding media. In another modification of the invention a plurality of such burners may be employed in series with successive burners taking suction on the effluent oil from the preceding burner and Venturi constriction combination. In another modification of the invention a portion of the hot crude oil, after passage through the Venturi constriction, may be 25 discharged through a suitable opening into the bore hole.

25 While the exact reasons for the increase of oil production upon heating are not known, it is quite possibly due to the decreased viscosity of the oil in the heated formation, the melting of wax deposits in the formation, the expansion of gas pockets in the formation during heating and the like.

30 Figure 1 shows an elevation view of an oil well employing a plurality of burners in order to heat

crude oil and the surrounding formation and also to provide energy for pumping the crude oil to the earth surface.

Figure 2 shows a partly sectional elevation view of the burner and Venturi constriction employed below the surface of the oil pool in Figure 1.

Figure 3 shows a cross-sectional view of Figure 2 taken through the plane 3—3.

Figure 4 shows a modification of the burner which is employed in Figure 1 above the surface of the oil pool.

Figure 5 shows a sectional elevation view of an alternative type burner which may be employed below the surface of an oil pool and wherein the oxygen is supplied to the burner through a central coaxial pipe passing through the one or more Venturi constrictions and wherein part of or all of the heated oil may be recycled to the oil pool in contact with the formation.

Figure 6 shows a method for piping oxygen-containing gas through a plurality of burners by means of a central coaxial pipe.

Figure 7 shows a means for igniting a burner within the well bore.

Figure 8 shows a sectional elevation view of a conventional type pump which may be employed at any suitable distance in the tubing above the burner-pump of this invention.

Perhaps the method and apparatus of this invention can best be understood by reference to the drawings.

Referring now more particularly to Figure 1, oil well 11 is drilled from earth surface 12 through various formations 13 into oil-bearing formation 14. Casing 15 is fitted with casing head 16 and passes downwardly through the well bore to within a short distance above oil-bearing formation 14. Casing 15 is fitted with a conventional gas outlet system indicated by pipe 17.

Tubing 18 is fitted with oil production line 19. Tubing 18 passes downwardly through casing head 16 and through well 11 to the bottom thereof. At the earth's surface compressor 20 takes suction on line 21 carrying oxygen-containing gas and forces such gas under pressure into oxygen supply line 22 which passes downwardly through casing head 16 and into well 11.

The lower portion of tubing 18 is fitted with plug 23 for protection in case of fall. Above plug 23 is located burner housing 24 enclosing burner 25. Burner housing 24 is fitted with a series of ports 26 which permit the flow of oil from the external oil pool 27 into contact with burner 25. Above burner housing 24 is located successively heat transfer unit 28, burner housing 29, heat transfer unit 30, coupling 31, burner housing 32, heat transfer unit 33 and connecting tubing 34 which passes to the earth's surface.

Heat generated by burner 25 is at least partially radiated by heat transfer unit 28 to the surrounding oil pool 27 which in turn heats the surrounding oil-bearing formation 14 by convection. The burner located within burner housing 29 and heat transfer unit 30 are located above the liquid level of oil pool 27 and radiate heat from the hot oil flowing therethrough to the surrounding oil-bearing formation 14 through the intervening gaseous phase by means of radiation. The oil flow from the formation is increased as a result of the heating regardless of the method of transfer. More effective heat transfer to the formation is obtained by radiation through the gas phase, however.

At the earth's surface electrical generator 35 supplies a suitable current to ignite the various

burners. The one terminal of generator 35 is connected to insulated ignition rod 36 which passes downwardly through tubing head 37 and tubing 18. The lower tip 38 of ignition rod 36 is non-insulated and comprises an exposed electrically conductive surface. The other terminal of generator 35 is connected to tubing 18 through casing head 16 to which it is grounded. Ignition rod 36 is slideable through the several burner elements and when passed into the proximity of a burner can be momentarily charged by generating a current in generator 35 to produce a spark of electric arc in the vicinity of the burner in order to ignite the burner.

Referring now more particularly to Figure 2, which shows an enlarged cross-sectional portion of the burner and heat transfer unit assembly, air or other oxygen-containing gas is introduced through line 22 into burner 25 whence it passes into the combustion zone surrounding burner 25. Burner housing 24 is submerged in the oil pool 27 and crude oil flows through the several ports 26 into contact with the combustion zone surrounding burner 25. A portion of such oil in contact with the combustion zone is continuously combusted in the flame to produce oxidation products which in turn transmit heat to the enveloping oil. The hot oil and gases flow upwardly through burner housing 24 and enter converging zone inlet 40 whence they pass through constriction zone 41 and thence to diverging zone outlet 42. The inlet 40 and outlet 42 of heat transfer unit 28 are surrounded by a plurality of heat transfer vanes 43 which transmit and radiate heat from the hot oil flowing within, through the chamber walls 44 to the surrounding media which may be either liquid or gaseous. The partially cooled oil leaving outlet 42 passes upwardly to a second burner housing 29 or other suitable coupling to the well tubing.

While only a single burner and heat transfer unit of Figure 1 has been shown in detail, the remaining burners, burner housings, and heat transfer units are of substantially the same construction as has been shown in Figures 1 and 2 with the exception that plug 23 is replaced with a suitable nipple or other coupling. Where the burner housing is not located below the liquid level of the oil pool as in the case of burner housing 29 and burner housing 32 of Figure 1, no ports are provided for the inlet of oil. In certain cases small ports with or without attached ducts may be provided to discharge a portion of the hot oil from the tubing to the surrounding media in order to provide more efficient heat transfer to the surrounding media. In all such cases, however, the combustion zone of each of the burners is of the submerged type wherein a part of the oil or gas is burned beneath the oil surface so as to heat the oil simultaneously.

Referring more particularly to Figure 4, the oxygen-containing gas may be introduced through line 58 to a plurality of burners 51 and 52, respectively, which are suitably displaced to permit the coaxial passage of oxygen-containing lines, burner rods for igniting burners and the like. The burner housing 53 shown in Figure 4 has no ports for the entry of oil and may therefore be employed above the liquid level within well bore in those cases where it is not desired to recycle hot oil.

Referring more particularly to Figure 3, which is a cross-section of Figure 2 through the plane 3—3, the hot oil passes through the center constriction 41. The walls 44 of the outlet 42 and

elements 43 represent the plurality of heat transfer units for radiating heat from the centrally carried hot oil through the walls 44 to the surrounding media.

Referring now more particularly to Figure 5, the line containing the oxygen gas may be passed coaxially within the string of tubing. In such a case the oxygen is introduced through line 60 which traverses the combustion zone, thereby preheating the oxygen-containing gas which flows downwardly through the line and issues from port 61 and valve assembly 62 whence it flows through burner chamber 63 into the combustion zone thereabove. Valve assembly 62 is so fashioned that the rotation of line 61 causes port 61 to enter into alignment with a corresponding port of the valve assembly, permitting the gas to issue when, and only when, such alignment has been obtained. Under this condition the flow of gas to the burner is controlled accordingly by the relative angular position of pipe 60. As in the previously described modifications, oil enters through a plurality of ports 64 into contact with the combustion zone created by the issuance of oxygen from the burner chamber 63. As above, the hot oil and combustion gases flow through a converging inlet 65 through a constricted zone 66 and thence into a diverging outlet 67. Heat from the hot oil passes through walls 68 to heat transfer vanes 69 whence it is transmitted by convection or radiation to the surrounding media. Where a plurality of burners are supplied through a single coaxial supply line the supply of oxygen to each of the several combustion zones may be controlled by the apparatus shown in Figure 6 wherein the oxygen is carried by line 75 and may be caused to flow through outlet 76 when port 77 is in alignment therewith and may be caused to flow through outlet 78 when port 79 is in alignment therewith, or through outlet 80 when port 79 is in alignment therewith. By employing such techniques one or several burners may be operated semi-independently of the remaining burners.

Referring again more particularly to Figure 5, where it is desired to employ a plurality of burners and heat transfer zones the bottom plug 70 may be replaced with a suitable tubular fitting adapted to receive other burners and heat transfer units and oxygen supply line 60 may be extended as shown in Figure 6 to a second burner of the type in Figure 5. In such a case the flow of oil and oxygen passes upwardly through the burner chamber and is partially combusted in the combustion zone. Under such conditions ports 64 are normally deleted.

When it is desired to recycle a portion of hot oil into the liquid oil pool in order to heat the formation, this may be accomplished by opening valve 72 in Figure 5 whereupon hot oil is discharged from the system through line 71 to the exterior.

In certain cases it is desirable to by-pass a portion of the oil being pumped from the oil pool around the combustion zone. In Figure 5 this may be accomplished by unplugging normally plugged line 75 so that a part of the oil in the oil pool is sucked into the lower pressure converging zone 65 and pumped upwardly with the heated oil.

Since every formation and the associated crude oil possess properties distinct from any other formation and its oil, the method of production must be varied to best suit the given individual

formation. For this reason, several methods of operation of the submerged flame heater may be employed to illustrate this point.

Where it is desired to recycle a portion of hot oil into the casing or to flow hot oil back into the formation in order to dissolve waxy deposits or remove foreign fluids plugging the formation at a considerable distance from the well bore, the well is either intermittently produced so that periodic back flow of hot oil into the formation occurs due to the hydrostatic liquid head and pressure build-up of the combustion gases in the tubing as the well is momentarily shut-in, or oil can be injected under pressure through the tubing and heated by the submerged flame prior to passage through ports 64 of Figure 5 into the formation.

Another method of recycling part of the hot oil into the casing consists of opening valve 72 of Figure 5 and adjusting the rate of oil production at the surface to a point where the increase in back pressure in the tubing will cause the desired quantity of recycle to discharge from the system via line 71 to the casing. In some cases, especially for heavy, viscous crude oils where heat transfer by convection is inefficient, it may be desirable to keep valve 72 open and operate at a minimum of back pressure in the tubing at the surface in order to suck the partially heated oil from the casing via line 73 into the tubing or the constricted section of the Venturi tube, thus mixing the hot oil with the casing oil.

Referring now more particularly to Figure 7, in certain cases such as when a coaxial oxygen supply line is employed, the method for igniting the burners as described in Figure 1 by the use of burner rod 36 becomes impractical. In such a case the shell of the burner 90 may be grounded to one potential of an electric generator while the other potential is connected to insulated electric lead 91 which passes within burner shell 90. Near the outlet 92 of the burner the insulated conductor is exposed so as to provide a sparking zone to the grounded burner shell. When current is passed through line 91 an arc occurs in the sparking zone to the grounded burner shell thereby causing the ignition of the oil in contact with the oxygen issuing from burner outlet 92.

Referring now more particularly to Figure 8, the pumps and heaters of this invention may be employed in connection with conventional pumps. In this event sucker rod 100 passes through tubing hanger 101 into tubing 102. Tubing 102 is fitted with a suitable locking means 103 which prevents movement of the outer barrel of pump 104 through locking ring 103 during reciprocation of sucker rod 100 which actuates the movable barrel of pump 104. During the reciprocation of pump 104 oil from lower chamber 106 within tubing 102 enters the lower inlet of the pump and is forced under pressure into the upper chamber 107 within tubing 102 whence it flows through production line 108. Combustion gases and other gases flow through pump 104 during such pumping of oil.

It is apparent that in its broad aspect this invention resides in the use of one or more burners of the submerged combustion type wherein oxygen is supplied to a combustion zone maintained within a body of combustible oil within a well bore wherein the heating of the oil produces a heat transfer media which may be employed ultimately to transmit a part of such heat to the oil-bearing formation whether by means of radiation or

by convection or by conduction in the case of recycle oil. Furthermore, the combustion gases are not wasted but are employed to assist in pumping the oil and in maintaining such oil in a continual state of turbulence during its transport to the earth surface so as to minimize the normal deposition of wax which readily occurs under these circumstances.

Furthermore, this invention relates to a new type of subsurface burner and heat transfer system for use in oil wells which accomplish heating and pumping.

The method of use of the burners and heat transfer units of this invention depends primarily upon the desired result. Very often only a single burner and a single heat transfer section need be employed, particularly when the oil is readily pumpable, with only slight heating and when a conventional pump is to be employed in conjunction therewith. Where the production from the well is extremely low indications are that the well is very amenable to heat treatment and under these conditions a plurality of burners and heat transfer units are normally employed in proximity of the oil-bearing formation.

Where a plurality of units are employed, and sometimes under other circumstances where but a single unit is employed, it is desirable that the heat transfer section be located above the liquid level of the oil pool and facing the exposed surface of the oil-bearing formation. Under these conditions there is obtained a maximum heat transfer from the heat transfer unit to the formation with a consequent maximum improvement in the flow of oil from the formation.

A special feature of this invention lies in the fact that the combustion of the oil takes place within an envelope of oil which is simultaneously heated by the combustion. In using the submerged heater the heat transfer from the flame to the formation is accomplished by a two-step process which may be arbitrarily designated as (1) direct, and (2) indirect. The direct heat transfer process takes place where the heat of the flame, by virtue of its submergence, is transferred directly to the enveloping oil. In this step there are no hot gas-to-metal or metal-to-liquid interfaces such as are necessary in the conventional flame heaters and accordingly the heater of this invention is not impaired by gas or liquid films, dirt, scale or other insulating barriers which might be deposited upon the burner surfaces. Thus the burner of this invention may be operated during long on-stream periods with a minimum of maintenance being required. Furthermore, the formation of hot spots due to corrosion or plugging within the metal tubes of the conventional heaters is not a problem.

The heat absorbed by the oil from the submerged flame is then transferred at least in part to the vanes surrounding the heat transfer section such as was shown in Figures 1 and 2. The heat transferred through such vanes ultimately reaches the formation by radiation or convection. In this second part of the heat transfer, i. e. through the vanes, the problem of varying oil temperatures is not met and a maximum control of the heat transfer can be had.

The heat transfer unit of the apparatus provided by this invention preferably has a converging zone and a diverging zone of the Venturi type. Units of this type are well known and are described, for example, in "Principles of Chemical Engineering" by Walker, Lewis, McAdams and Gilliland, 1937 edition on page 68 et seq. Pref-

erably the converging zone has a total angle of about 25° and the diverging zone has a total angle of about 7°.

The foregoing disclosure of this invention is not to be considered as limiting since many variations and modifications can be made by those skilled in the art without departing from the spirit and scope of the following claims.

I claim:

1. In a method for increasing production from an oil well in which a well tubing communicates from the earth surface to a body of petroleum at the bottom of the well bore, the steps which comprise introducing a stream of oxygen-containing gas directly into and below the surface of said body of petroleum and igniting the mixture of oxygen-containing gas and petroleum vapor which is thereby formed to produce a flame submerged in said body of petroleum, said stream of oxygen-containing gas being directed upwardly within said body of petroleum and towards the opening in said well tubing thereby causing said flame and the combustion products thereof to be directed upwardly and towards said opening in said well tubing.
2. The method of claim 1 wherein the oxygen-containing gas is air.
3. In a method for increasing production from an oil well in which a well tubing communicates from the earth surface to a body of petroleum at the bottom of the well bore, the steps which comprise introducing a stream of oxygen-containing gas directly into and below the surface of said body of petroleum; igniting the mixture of oxygen-containing gas and petroleum vapor which is thereby formed to produce a flame submerged in said body of petroleum, said stream of oxygen-containing gas being directed upwardly within said body of petroleum and towards the opening in said well tubing thereby causing said flame and the combustion products thereof to be directed upwardly and towards said opening in said well tubing and by their jet action to assist in raising non-combusted petroleum through said tubing; withdrawing said combustion products and non-combusted petroleum upwardly through said tubing, and transferring heat from said combustion products and non-combusted petroleum to the surrounding formation.
4. The method of claim 3 wherein the oxygen-containing gas is air.
5. The method of claim 3 wherein the transferral of heat from the combustion products and non-combusted petroleum to the surrounding formation is through the gas phase existing above said body of petroleum.
6. The method of claim 3 wherein a portion of the non-combusted petroleum is returned to the body of petroleum in the well bore subsequent to the transfer of heat therefrom.
7. A well heating apparatus comprising a combustion chamber having a fluid outlet in the upper surface thereof and at least one port adapted to permit the flow of liquid into said chamber when the latter is submerged in a body of said liquid, gas inlet means positioned within said chamber and directed towards the fluid outlet thereof, ignition means positioned within said chamber adjacent said gas inlet means, and heat transfer means having a fluid outlet and a fluid inlet, said heat transfer means being attached to said combustion chamber in such manner that the fluid inlet of the heat transfer means is in register with the fluid outlet of the combustion chamber.
8. A well heating apparatus comprising a cylin-

drical combustion chamber having a closed lower surface, an open upper surface and a lateral surface provided with at least one port adapted to permit the flow of liquid into said chamber when the latter is submerged in a body of said liquid, gas inlet means positioned within said chamber and having a gas outlet directed towards the opening in the upper surface of said chamber, ignition means positioned within said chamber adjacent to said gas outlet, and tubular heat transfer means attached to said combustion chamber having a fluid inlet in register with the opening in the upper surface of said combustion chamber and a fluid outlet adapted to being joined to a well tubing.

9. A well heating apparatus according to claim 8 wherein the tubular heat transfer means is of Venturi shape having exterior fins.

10. A well heating apparatus according to claim 8 and comprising means for withdrawing from the upper portion of the heat transfer means a portion of the fluid passing through said heat transfer means.
